UNITED STATES PATENT OFFICE.

JAMES C. HARRIS, OF DALLAS, TEXAS.

TOY GUN.

Application filed January 25, 1927. Serial No. 163,385.

This invention relates to a toy gun and it has particular reference to a toy gun adapted for shooting rubber and other elastic bands, and its principal object resides 5 in the provision of a harmless but interesting toy, having the form and characteristics of an actual weapon, upon which may be placed a multiplicity of rubber bands to be released in rapid succession at a target with remarkable accuracy.

Another object of the invention resides in certain facilities by which it is possible to extend without difficulty the length of the barrel of the gun, to adjust the same 15 according to the size and elasticity of the bands comprising the ammunition.

The invention further aims among its objects to provide a novel co-ordinating trigger and band retaining mechanism, whereby 20 with a minimum amount of moving parts, the bands may be released successively with accuracy and precision.

With these foremost objects in view, the invention has particular reference to its salient features of construction and arrangement of parts by which the said objects are attained, and which will become apparent from the following detail description and 30 illustrated in the accompanying drawings, wherein:

Figure 1 represents a longitudinal cross-sectional view of a toy gun constructed according to the present invention.

Figure 2 is a fragmentary detail view of 35 the barrel extension adjustment, and

Figure 3 is a side elevational view of the gun on which is operatively disposed a series of rubber bands.

Continuing now more in detail with the 40 drawings, it will be noted that while the latter illustrates a facsimile of the revolver type of weapon, the rifle may be imitated as well without departing from the construction of parts employed and herein described.

The pistol grip 1 and barrel 2 are composed 45 preferably of a single piece of material such as wood for economy, and with a suitable saw or like instrument, an opening in the form of a slot 3 is made in the breech portion of the body. Within the slot 50 3 and accurately alined with the barrel 2 is a toothed wheel 4, whose teeth are not directed radially outward from the wheel but whose ends, as they appear at the upper 55 portion of the device in the rotation of the

wheel are all directed rearwardly with respect to the barrel 2 as apparent particularly in Figure 1. This wheel is mounted to freely rotate upon a rivet 5, passed through the gun, and is controlled in intermittent rotation by the member 6 serving a dual purpose as a verge and trigger.

The bands 7 are stretched over the nozzle of the gun and constrained from dislocation by a notch 8 provided therein, and then placed in the spaces intermediate the teeth on the wheel 4, the teeth by their character as above explained, serving as hooks to receive one end of the several bands. The tension of the bands will of course 60 cause the wheel to rotate forwardly to release the bands in succession.

The controlling or actuating member 6 therefore when in one position, is designed to constrain the wheel 4 from rotating and 65 to control the release of the bands at will, and in such capacity, the finger designated at *a* engages the teeth of the wheel 4 consecutively when the lower end of member 6 is positioned forwardly, as the bands 7 are 70 released and the wheel rotates.

The trigger element 6 is likewise formed to define a stop *b* somewhat below and spaced from the finger *a*, hence providing a form of escapement mechanism in which 75 both the finger *a* and stop *b*, contacting different teeth of the wheel, co-ordinate to control the tension of the bands upon the wheel 4 through a single trigger, which is equibalanced on the pivot 9. It will therefore 80 be seen that a movement of member 6 on its pivot releasing finger *a* will at the same time cause stop *b* to approach another tooth.

Consequently, when the bands 7 are placed 85 as described and shown in Fig. 3, and as the wheel and member 6 are shown in Fig. 1, the finger *a* contacts the teeth of the wheel 4, which tends to move the finger *a* away from the teeth, and the lower end of the trigger 6 rearwardly, to bring the stop *b* 90 in contact with teeth in advance of the one released by *a*.

Each time the trigger is actuated to release the finger *a*, the removing bands maintain 100 the tension on the wheel, to urge the teeth successively against the stop *b*, in which position the wheel may be held positively by the operator pressing the lower end of the trigger rearwardly by the finger 110

of his hand. When the operator releases the trigger, the wheel will advance and move the lower end of the trigger forwardly and the finger *a* rearwardly in a position preparatory to the release of another band, when the lower end of the trigger is again engaged by the operator's finger.

This operation may be carried out as long as a band remains upon the gun, the wheel 10 4 being alternately engaged and released by the parts *a* and *b*.

The barrel extension arrangement illustrated in Figures 1 and 2 consists as shown of a slot 10 along the underside of the barrel 15 2 and partially therethrough, and through which a number of pins 11 are driven. A metal strip 12 having therein L shaped slots 13 is arranged to be inserted into the slot 10 in order that the pins 11 may be received 20 in the slot 13 and slid rearwardly with respect to the gun body to lock the pins within the longitudinal positions of the slot to securely hold the strip. Should a larger rubber band be used requiring greater tension, 25 it is necessary only to replace the metal strip 11 on the pins nearer the end of the barrel 2 whereby the end of the strip will extend beyond the end of the gun.

Manifestly, the construction shown is 30 capable of considerable variation and such variation as is in keeping with the appended claims is considered within the spirit of the invention.

What is claimed is:

35 1. In a toy gun a barrel having a slot formed therein remote from its forward end; a wheel rotatably mounted in said slot and having peripheral teeth formed at a common angle with respect to their respective radii for the reception of elastic bands to be stretched over the end of said barrel, a trigger member pivoted adjacent to said wheel, and spaced contact means integral with said trigger member engageable with the teeth of said wheel to successively hold and release said teeth, and other means integral with said member for manually actuating the latter on its pivot.

50 2. A toy gun having a barrel and a slotted grip portion, a wheel rotatably mounted in said slot and having peripheral teeth for holding thereon elastic bands under tension, an escapement mechanism comprising a lever member pivoted adjacent said wheel and having one end engaging the said teeth successively as the wheel rotates, a stop device

spaced from said engaging end for contacting teeth singly when the said end is released from the wheel, and the opposite end projecting below the said slot to serve as a 60 trigger member by manual actuation, to release the said engaging end and stop alternately from the teeth and the bands from the teeth.

3. A toy gun having a barrel and a slotted grip portion, a wheel rotatably mounted in said slot and having peripheral teeth for holding thereon elastic bands under tension, a lever member pivoted adjacent said wheel and having at one end a pair of longitudinally spaced contact shoulders engaging the said teeth alternately as the wheel rotates, and the opposite end projecting below the said slot to serve as a trigger member by manual actuation, to release the several teeth singly 70 75 from the said shoulders and the bands from the teeth.

4. A toy gun having a barrel and a slotted grip portion, a wheel rotatably mounted in said slot and having peripheral teeth for holding thereon elastic bands under tension between the teeth and the outer end of the barrel and thereby normally actuate the wheel in rotation, a lever member pivoted adjacent said wheel and having spaced portions 80 85 for engaging the said teeth successively as the wheel rotates, and projecting below the said slot to serve as a trigger member by manual actuation to release the said teeth from the lever.

90 5. A toy gun having a barrel and a slotted grip portion, the forward portion of said barrel having a longitudinal slot spaced from the slot in the grip portion and the longitudinal slot opening throughout its length to permit insertion therein of a barrel extension, adjustably, the slotted portion of the barrel having spaced, transverse pins positioned lengthwise thereof and said extension having in its upper edge spaced L- 95 notches for receiving therein certain of said pins whereby the outer end of the extension may be adjusted toward and from the end of the barrel, means in the grip portion for holding thereon elastic bands under tension 100 105 between said means and the outer end of said extension, and means projecting below the grip slot for releasing the bands from the said holding means.

In testimony whereof I affix my signature.

JAMES C. HARRIS.
